Int. Cl. D14—01

U.S. Cl. D56—4 R

FIG. 1

FIG. 2

FIG. 3

FIG. 4

FIG. 1 is a left side, top and front perspective view of a record player, showing my new design;

FIG. 2 is a left side, top and front perspective view, the transparent dust cover being removed and omitted for convenience of illustration;

FIG. 3 is a right side, bottom and rear perspective view, the transparent dust cover being removed and omitted for convenience of illustration; and

FIG. 4 is a front elevational view thereof.

Portions of the figures are shaded to indicate contrast in appearance, and portions are diagonally lined to indicate transparency.

The structure which would be visible through the transparent covers in FIGS. 1 and 4 has been omitted for convenience in illustration.

I claim:

The ornamental design for a record player, as shown and described.
